WORKPIECE-LOCATING VISE FOR USE IN A MACHINE-TOOL

Robert Moll, Geneva, Switzerland, assignor to Condor S.A., Courfaivre (Jura bernois, Switzerland), a corporation of Switzerland

Filed Feb. 15, 1962, Ser. No. 173,454

Claims priority, application, Switzerland, Feb. 17, 1961, 1,997/61

4 Claims. (Cl. 269—25)

This invention relates to a workpiece-locating vise for use in a machine-tool.

According to the present invention the vise comprises supporting structure on which are supported two jaws each controlled by an hydraulic servo-motor supplied with fluid under pressure from a general distributor, and control means for automatically centering a workpiece to be machined by the machine-tool on a reference axis, said control means comprising a secondary distributor consisting of a sheath and of a slide valve member slidably mounted in the sheath, said sheath being itself mounted in said supporting structure for sliding displacement parallel to the slide valve member, at least one of said servo-motors being supplied via a conduit with fluid whose flow, pressurization and exhaustion are controlled by a plurality of ports formed in the sheath, the opening and closing of these ports being operated by the slide valve member, the position of the sheath being made dependent on the position of one of the jaws and the position of the slide valve member being made dependent on the position of the other jaw so that by means of said ports the workpiece to be clamped will always be located in the same centering position irrespective of its diameter.

For a better understanding of the invention and to show how the same may be carried into effect, one constructional form of vise according to the invention will now be described, by way of example, with reference to the accompanying drawing which is a diagrammatic cross-section of the vise.

The illustrated workpiece-locating vise is particularly, but not exclusively, intended for use in a machine-tool for lathing and centering workpieces which are subsequently to be finished by other machines, for example the machine-tool disclosed in the specification of my co-pending patent application No. 173,453, filed February 15, 1962, now Patent No. 3,110,082, issued November 12, 1963.

The illustrated workpiece-locating vise comprises a supporting frame 1 having clamping means 2 for mounting the vise on a rod or tube 3 of a machine-tool. A fixed slide-bar 4 to which the frame 1 can also be releasably clamped is provided on the machine-tool to prevent rotary movement of the vise about rod 3. On the supporting frame 1 are mounted two jaws 5 and 6 which are controlled by cylinder and piston article clamping units each comprising a servo-motor including a first cylinder 7 and a servo-motor including a second cylinder 8, respectively. Jaw 5 consists in the present instance of a stem projecting from the piston 9 of the servo-motor 7. Jaw 6, which is formed with a V-shaped notch 10, is slidably mounted in a guide 11 of the supporting frame 1. The jaw 6 is rigidly connected to the piston 12 of servo-motor 8 by a stem 13.

The supporting frame 1 is also formed with a bore 14 extending parallel to the axis of movement of jaws 5 and 6. Bore 14 accommodates a secondary pressurized fluid distributor 15 in the form of valve means including a sheath 16 and a slide valve member 17 slidably mounted in sheath 16. Sheath 16 is capable of limited sliding movement in the bore 14 as determined by a screw 18 which extends through a threaded bore 19 of the sup-

2

porting frame 1 and whose point projects into a groove 21 formed in sheath 16. The sheath 16 is also formed on one of its sides with ports 22, 23 and 24 through which the outer surface of the sheath communicates with its internal bore 25. The slide valve member 17 is formed with an annular groove 26 the width of which corresponds substantially to the distance separating ports 22 and 23 in the sheath. On the side opposite ports 22 and 23, the sheath 16 is provided with a port 27, which is located in an axial position intermediate ports 22 and 23 and which opens in a groove 28 formed in the sheath 16. Ports 22 and 23 open in grooves 29 and 30, respectively, groove 30 extending to port 24.

The servo-motors 7 and 8 are supplied with oil under pressure from a general distributor 31 including two solenoid-operated valves 32 and 33, of which one is open to the atmosphere when the other connects the supply circuit of servo-motors 7 and 8 to the source of oil under pressure. Conduit 34, which is controlled by valve 32, is connected at 35 and 36 to the servo-motors 7 and 8. Conduit 37, which is controlled by valve 33, directly feeds servo-motor 7 by opening at 38 into the cylinder thereof. This conduit 37 is extended by a passage 39 drilled in the supporting frame 1 and terminating at port 40 in groove 30 of sheath 16. A passage 41, which is also drilled in the supporting frame 1 and which terminates at 42, establishes communication between the groove 29 and an exhaust 43. Groove 28 formed in sheath 16 communicates with servo-motor 8 via a port 44 drilled in the supporting frame 1, and via a conduit 45 which opens in the servo-motor 8 through a passage 46.

As will readily be understood from inspection of the circuitry for feeding servo-motors 7 and 8, the servo-motor 7 is directly supplied with oil from the general distributor 31 for operative movement in both directions. But servo-motor 8 is only directly fed with oil by valve 32 for a vise releasing stroke, it being indirectly controlled by the secondary distributor 15 to bring about a gripping action of the jaws 5 and 6 on a workpiece 47 to be held. The secondary distributor 15 forms part of means for self-centering workpiece 47 in relation to a reference axis. In this connection, the axial position of sheath 16 is made dependent on the position of jaws 6 through the intermediary of a lever 48 which is pivotally mounted at 49 on the supporting frame 1 and which acts at one end 50 against the adjacent end of sheath 16 and at its opposite end 51 against the end of a rod 52 projecting from the piston 12 of servo-motor 8.

The slide valve member 17 is subjected to the other jaw 5 through the intermediary of a connecting arm member 53, one end portion of which is engaged over a threaded extension 54 of the slide valve member 17, and the other end portion of which is engaged over a rod 55 projecting from the piston 9 out of the servo-motor 7. Member 53 is rigidly secured to the rod 55 by a screw 56. But the position of member 53 on the threaded extension 54 of the slide valve member 17 is adjustable by means of a nut 57 and of a knurled nut 58 between which is clamped the end portion 59 of member 53.

As shown by the drawing, the diameter of piston 9 of servo-motor 7 is smaller than the diameter of piston 12 of servo-motor 8. The servo-motor 7, which is supplied with oil directly from the general distributor, is intended to exert a constant pressure on the workpiece 47 by its jaw 5 in the course of a clamping operation, the position of jaw 5 being corrected by the greater pressure exerted by jaw 6 actuated by piston 12 of greater diameter. However, the oil supply to servo-motor 8 is regulated by the secondary distributor 15. In this connection and as shown by the drawing, when the jaws 5 and 6 have been pressed into engagement with the workpiece preparatory

to positioning on the reference axis R, the servo-motor 3 is supplied with oil under pressure by the solenoid-operated valve 33 via conduit 37, passage 39, groove 30, port 23, annular groove 26, groove 28, passage 44 and conduit 45. The pressure exerted in servo-motor 3 is however limited because a leakage of oil occurs via port 22, groove, 29 and passage 41 towards the exhaust outlet 43.

Supposing that during clamping of workpiece 47, the jaw 6 is too far forward in relation to jaw 5, the slide valve member 17, which is lagging, wholly uncovers port 22 by means of its groove 26 and closes the port 23 for admitting oil under pressure, thereby interrupting the supply of oil under pressure to the servo-motor 3 and bringing it to a stop. The servo-motor 7 can thus proceed with the forward movement of jaw 5 thereby restoring the balanced condition of jaws 5 and 6 by, if need be, pushing back jaw 6.

If, however, it is jaw 5 that is too far forward in relation to jaw 6, the slide valve member 17 closes leakage port 22 and causes port 23 for admitting oil under pressure to communicate with its groove 26. Conduit 45 will thus convey a large flow of oil to the servo-motor 3. As the working area of piston 12 of servo-motor 3 is greater than that of piston 9 of servo-motor 7, the greater thrust of piston 12 enables the latter to push jaw 5 backwards to bring workpiece 47 into its centered position on the reference axis, in which position the thrusts exerted on jaws 5 and 6 become stabilized.

A demultiplying mechanism is provided in the transmission between the V-shaped jaw 6 and the secondary distributor constituted in the illustrated embodiment by the sheath 16. This demultiplying mechanism is in fact constituted by the lever 43 and is made necessary by the presence of the V-shaped jaw 6. Inasmuch that the vise must be able to clamp workpieces of different diameters and always to center these workpieces on the same reference axis, the possible clamping movement of jaw 6 must necessarily always be greater than that of jaw 5 which has the appearance of an ordinary pusher. If the angle of the V-shaped notch 10 of jaw 6 is "2a" and the amplitude of the clamping displacement of jaw 5 is "A," then the amplitude of the clamping displacement of jaw 6, termed "B," would be equal to

$$\frac{A}{\sin a}$$

It therefore follows that the demultiplication of the displacement of jaw 6 in relation to sheath 16 must be in the ratio of $\sin a$. The ratio between the sheath arm 60 of lever 43 and the longer arm 61 is therefore equal to $\sin a$.

Between the sheath 16 and the slide valve member 17 are provided thrust means tending to move the sheath 16 and the member 17 away from one another in order to take up any transmission play in the return motion from piston 12 to the secondary distributor 15. The thrust means is constituted by a chamber 62 of sheath 16, which chamber is constantly subjected via port 24 to oil pressure during movement of jaws 5 and 6 for a clamping operation.

The vise is released by reversing the flow of oil in the general distributor 31, i.e. by feeding oil under pressure into conduit 34 thereby causing the pistons 9 and 12 of servo-motors 7 and 3, and hence jaws 5 and 6, to move away from one another.

Of course, conduit 37 will have to be opened to the atmosphere by the solenoid-operated valve 33 to enable jaws 5 and 6 to be moved apart.

I claim:

1. A machine tool locating vise comprising, a frame having a bore provided with fluid pressure ports and an exhaust port, first and second fluid cylinder and piston article clamping units,

a primary source of fluid pressure operating in conjunction with valve means to move the pistons of said first and second article clamping units to article clamping position,

valve means in said bore comprising a sheath and a slideable valve telescoping therewith, said sheath and valve having portions exposed outside of the bore, and said valve having an annular groove adapted to cooperate with said pressure ports to supply pressure to the second fluid cylinder and piston article clamping unit and also communicating with said exhaust port, and means actuated respectively by the exposed portions of the sheath and the valve to hold the pistons and clamping members in final adjusted relation.

2. A machine tool locating vise as claimed in claim 1, wherein said means holding the pistons and clamping members in final adjustment includes, on the one hand, a connecting arm attaching said valve to said first clamping unit and, on the other hand, a rockable lever supported by said frame and having its opposite ends engaged by said sheath and said second clamping unit, said lever being supported at a point substantially closer to one end than the other to provide a demultiplication of the force exerted by said sheath.

3. A machine tool locating vise as claimed in claim 2, wherein said connecting arm provides a rigid attachment between said valve and said first clamping unit, and means on said valve for adjusting the positions of said valve and first clamping unit relative to one another to permit a modification of the position of the reference axis into which each workpiece is to be brought.

4. A machine tool workpiece locating vise, comprising, a frame having a bore provided with a primary fluid pressure passage, an exhaust passage, a clamping jaw including an article engaging stem and actuating stem carried by a piston operating in a first cylinder having pressure and exhaust ports at opposite sides of the piston,

a centering jaw including a supporting stem and an actuating stem both connected to a piston of larger diameter than said first mentioned piston and operating in a second cylinder having pressure and exhaust ports at opposite sides of the piston, said clamping and centering jaws operating in a plane parallel to said bore,

a sheath having limited slideable movement in said bore and having a first longitudinal groove communicating with said exhaust passage, said sheath being tubular at one end and exposed beyond the frame at the other end, said sheath also having a second longitudinal groove in communication with said primary fluid pressure passage, said first and second grooves provided with a secondary and primary port, respectively, extending inwardly through the wall of said sheath,

a valve member slidably mounted in the tubular portion of the sheath and having a medial annular groove adapted to span and communicate with said primary and secondary ports, one end of said valve member projecting from said frame,

a connecting arm attaching the projecting end of said valve member to the actuating stem of said clamping jaw,

an equalizing pressure port through said sheath and in constant communication with said annular groove on the one hand and connected on the other hand to said second cylinder,

a lever rockably supported medially on the frame and having one end engaging the actuating stem of said centering jaw and the other end engaged by the exposed end of said sheath,

and a source of fluid under pressure including a pair of valves, one of said valves supplying fluid to said pressure port of said first cylinder and also communicating with said primary fluid pressure passage, whereby when fluid under pressure is admitted to said pressure port of said first cylinder, said slidable valve member is moved to permit the flow of fluid from said primary port through said annular groove and equalizing pressure port to the pressure port of said second cylinder.
